H. FRIEGL

ART OF MANUFACTURING ICE

Filed Oct. 22, 1923

Inventor:

Herman Friedl,
By appointment of
Cotton Mills
Atkins

UNITED STATES PATENT OFFICE.

HERMAN FRIEGL, OF CHICAGO, ILLINOIS

ART OF MANUFACTURING ICE.

Application filed October 22, 1923. Serial No. 670,003.

To all whom it may concern:

Be it known that I, HERMAN FRIEGL, a citizen of the United States, residing at Chicago, in the county of Cook and State of Illinois, have invented a new and useful Improvement in the Art of Manufacturing Ice, of which the following is a specification.

It is the common practice in the manufacture of ice to place the cans containing 10 the water, from which the ice is to be formed, in a refrigerating bath, as for example brine, the temperature of which is reduced to the desired degree for producing the refrigerating effect by subjecting it to a 15 refrigerating medium.

The water in the cans is frozen from the bottom and the sides upwardly; the water last to freeze being, at the top portion, in the form of a downwardly-tapering body 20 surrounded by ice. It has been found in practice that according to the methods hitherto employed it requires approximately eight hours to freeze this remaining body of 25 water, due to the fact that the refrigerating brine is at substantially the same level as the top of the ice when all the water in the can is frozen.

I have discovered that by subjecting the water in the can, to be formed into the ice 30 cake, to a refrigerating bath, the level of which extends to such a height relative to the water in the can that when the water is frozen the top of the ice cake extends a substantial distance below the level of the 35 refrigerating bath a solid cake of ice may be formed in very much less time than in accordance with the practice heretofore employed, thereby greatly reducing the cost of manufacturing ice.

40 Referring to the accompanying drawing, the figure therein shown illustrates, by a view in vertical sectional elevation one end of a brine tank and one of the ice cans immersed therein, the arrangement shown 45 being suitable for practicing my improved method.

In the apparatus shown, the brine tank is represented at 1, this tank being of any suitable construction and which, in practice, 50 would preferably be of such proportions as to be adapted to receive pluralities of rows of cans, one of which is represented at 2, in which the ice is to be formed. As shown, and in accordance with structures of this 55 character as commonly provided, the ice cans are introducible into, and withdrawable

from, the bath of refrigerating liquid 3, such as refrigerated brine, through the upper closure-equipped openings 4 in the top of the tank 1, one of these openings only being 60 shown.

In the manufacture of the ice the can 2 is filled with water from which the ice is to be formed, of such an amount that when the water is frozen solid throughout its extent, 65 the top of the block of ice therein produced will extend a substantial distance below the level of the refrigerating brine 3 and preferably a distance below the level of the refrigerating brine substantially not less than 70 one-half of the width of the can, the width referred to being the shorter dimension crosswise of the can where the can is of oblong shape in cross section. For commercial reasons, it is further preferred that the 75 amount of water charged into the can be such that the top of the block of ice will extend below the level of the refrigerating brine a distance substantially equal to form about one-half to about three-quarters of the 80 width of the can, and more preferably that this distance be about three-quarters of the width of the can. In the particular arrangement shown, the dotted line 5 illustrates, by way of example, the level of the water 85 charged into the can in accordance with the preferred manner of practicing my invention, and the full line 6 represents the upper surface of the completely-formed ice-block.

The effect of encircling the can with the 90 refrigerating medium above the level to which the ice when formed extends, in addition to encircling the can throughout that portion thereof at which the formed ice-cake extends, is that the air in the upper part of 95 the can is refrigerated, thereby forcing upward and out of the can the warm air therein, with the result of very greatly expediting the formation of a solid block of ice in the can.

100 It has been found that by the employment of the method described herein it is possible to manufacture cakes of ice of any given dimensions in a much shorter length of time (without corresponding increase of 105 cost) than is required to produce an ice-cake of the same dimensions in accordance with methods previously employed; and also that merely by slightly deepening the bath of refrigerant and the cans, in an existing ice-plant employing old methods, more ice can 110 be produced in a given length of time.

- Thus in utilizing such a plant provided for producing 400 pound cakes of ice, by merely extending upwardly the side walls of the tank and cans, each a distance as short as substantially one-half of the width of the cans and charging into the tank sufficient refrigerant to raise its level a distance corresponding to the addition made to the side walls of the tank and cans, as stated, and charging 400 pounds of water into each can, a greater quantity of ice is produced than could be produced in the plant constructed and operated in accordance with prior practice. This result is produced for the reason that the upper level of the water in the cans is always so far below the level of the refrigerating bath that rapid refrigeration takes place up to the top of the body of water and without the formation of a cup-shaped opening in the top of the ice-cake.
- Where the cans used are of the same general construction as now commonly provided, such character of cans being preferably employed in practicing my invention, the charging of the same with the preferred amount of water, as above stated, would not cause the charged cans to be of sufficient weight to sink into the refrigerating bath the desired distance, for causing the water level to be at the desired elevation above referred to. It is thus necessary to augment the combined weight of the cans and their contents, and this may be accomplished in any desirable way, as for example by so weighting the cans that they will become immersed in the bath to the desired degree by gravity, or, if desired, the cans may be made lighter and forced downwardly to the desired position, in which position they may be held by any desirable means, as, for example, by means of pins, one of which is represented at 7, which are adapted to be introduced into openings 8 in the depending beams 9 of the top of the brine tank and at
- their inner ends overlap the upper edges of the cans, or, if desired, any suitable catch mechanism for this purpose may be provided.
- While I have illustrated and described a particular apparatus adapted for the practicing of my improved method, I do not wish to be understood as intending to limit it thereto as the method may be practiced in other ways without departing from the spirit of my invention.
- What I claim as new, and desire to secure by Letters Patent, is:
1. The method of manufacturing ice, which consists in subjecting the receptacle in which the water is to be frozen to a refrigerating bath the level of which extends to such a height relative to the water in the receptacle that when all of the water is frozen the top of the ice cake is a substantial distance below the level of the refrigerating bath.
  2. The method of manufacturing ice, which consists in subjecting the receptacle in which the water is to be frozen to a refrigerating bath the level of which extends to such a height relative to the water in the receptacle that when all of the water is frozen the top of the ice cake is below the level of the refrigerating bath a distance substantially not less than one-half the width of the receptacle.
  3. The method of manufacturing ice, which consists in subjecting the receptacle in which the water is to be frozen to a refrigerating bath the level of which extends to such a height relative to the water in the receptacle that when all of the water is frozen the top of the ice cake is below the level of the refrigerating bath a distance substantially equal to from about one-half to about three-quarters of the width of the receptacle.

HERMAN FRIEDL
